BUTTON AND MEANS FOR SECURING IT TO GARMENTS

Application filed June 14, 1929. Serial No. 370,939.

This invention relates in general to buttons and more particularly to buttons or button forms especially adapted for use upon fur garments.

The objects of the invention are to provide a button of the character described having novel and improved construction and combination of body or head and a shank, whereby the body may have securely fastened thereto a cover and the shank provides ample distance between the body and the portion of the garment to which the button is applied, to receive an overlapping portion of the garment containing a buttonhole or button loop, the shank sustaining the wear from the buttonhole or button loop so as to relieve the underside of the cover and the fastening from such wear; to provide such a button comprising a block having a disc-like body provided with a flat underside and an integral shank projecting from said flat side coaxially with the body, and an opening extending through both said shank and said body to receive means for fastening a button to a garment or the like; to provide in such a button a novel construction and combination of the body and shank whereby a maximum space is provided between the garment and the underside of the head or the button with the shank of minimum length, and to obtain other advantages and results as will be brought out by the following description.

Referring to the accompanying drawing in which corresponding and like parts are designated by the same reference characters—

Figure 1 is a transverse vertical sectional view through a button and means for securing it to a garment, showing the button as applied.

Figure 2 is a composite detached perspective view of the button and its fastening means, and

Figure 3 is a view similar to Figure 1 showing a modified form of fastening means.

Specifically describing the embodiment of the invention illustrated in Figures 1 and 2 of the drawings, the button comprises a block 1 having a disc-like body or head 2, the underside 3 of which is substantially flat, while the upper side 4 is preferably convexly

curved. An integral shank 5 projects from the flat side 3 of the body substantially coaxially therewith, and the sides of the shank meet the flat side 3 of the body at substantially right angles as indicated at 6. Preferably the body 2 is circular, and the shank 5 is preferably cylindrical with straight sides. An axial opening 7 extends through the body and shank to receive fastening means for securing the button to a garment. Preferably the body and shank are formed of material, such as wood, capable of receiving and holding a screw.

One manner of fastening the button to a garment comprises a wood screw 8 having a head 9 and a shank 10 larger in diameter than the opening 7, in combination with a washer 11 which has a countersunk opening 12 to receive the screw 8. The button is arranged at one side of a portion A of the garment with the end of the shank in abutting relation to the garment. The washer 11 is arranged at the other side of the garment and the screw 8 is passed through the opening 12 of the washer and through the material of the garment and screwed into the opening 7 of the button. The material of the garment is thus securely clamped between the washer 11 and the end of the shank. The overlapping portion B of the garment may have a button-hole or button loop C which is slipped over the head or body of the button and contacts with the sides of the shank, as shown in Figure 1. It will be noted that the straight sides of the shank and the meeting thereof at right angles to the flat underside of the body provides a maximum of space for the button loop between the portion A of the garment and the flat side of the button, without an objectionably long shank.

The particular combination and arrangement of the flat side 3 of the body and the shank further especially adapts the button to receive a cover. As shown in Figure 1 of the drawing, the cover consists of a piece 13 of fur or the like which has its edges secured in close contact with the underside 3 of the body of the button in surrounding relation to the shank. The means for fastening the cover 2 of the button may be ordinary

stitching commonly used by which the edges of the cover are drawn together.

With this construction the shank 5 receives all of the wear from the buttonhole or button loop and the strain upon the portion A of the garment is widely distributed by the large end of the shank and the washer 11. Therefore the button will remain securely fastened to the garment for a long time.

- 5 10 A modified form of means for attaching the button to the garment is shown in Figure 3 of the drawing and comprises a disc 14 of suitable material, such as leather, which overlies the outer surface 4 of the button and has spaced openings 15 therein through which is threaded a cord 16. The ends of the cord pass through the opening 7 of the button and an opening 17 in the garment. At the side of the garment opposite the button is located another disc 18 identical with the disc 14 and having openings 19 through which are threaded the extremities of the cord which are knotted at 20 at the outer side of the disc. The two discs 14 and 18 in combination with the cord 16 thus serve to securely attach the button to the garment.

Having thus described my invention, what I claim is:

1. As an article of manufacture, a button 30 comprising a block having a disc-like body provided with a flat underside and an integral shank projecting from said flat side coaxially with the body, the sides of said shank meeting said flat sides of said body at substantially right angles, and a covering for said body comprising a piece of material having its edges secured in close contact with said flat side of the body around said shank.
2. As an article of manufacture, a button 40 comprising a block of wood having a disc-like body provided with a flat underside and a convexly curved upper side, and an integral cylindrical shank projecting coaxially from said flat underside with straight sides 45 meeting said flat underside at right angles, there being a hole extending entirely through said body and said shank and coaxially therewith to receive fastening means for securing the button to a garment.
3. As an article of manufacture, a button 50 comprising a block of wood having a disc-like body, and an integral shank projecting coaxially from the underside of said body, there being a straight walled hole extending entirely through said body and said shank coaxially therewith, and fastening means for securing said button to a garment comprising a wood screw having a shank of greater diameter than said hole in the button, and a 55 washer to be arranged between the head of said screw and the end of said shank.

JOSEPH ARBES.
